UNITED STATES PATENT OFFICE.

JAMES L. RAY, OF SWARTHMORE, PENNSYLVANIA, ASSIGNOR TO WESTINGHOUSE ELECTRIC & MANUFACTURING COMPANY, A CORPORATION OF PENNSYLVANIA.

TURBINE BLADE.

Application filed December 15, 1927. Serial No. 240,230.

My invention relates to elastic fluid turbines, and more particularly to the blading thereof, and it has for an object to improve the construction of such blading.

5 In the operation of elastic fluid turbines, vibrations occur which cause the blades to vibrate about their root portions more or less in the direction of least resistance. This repeated flexing and reversal of stress, in 10 time, causes the blades to rupture, or to become cracked along the thin extreme edge portions where the bending stress is the highest. In the thicker portions of the 15 blade, the unit stresses are lower and moreover, these portions are better adapted to withstand such stresses.

More particularly, therefore, an object of my invention is to provide for relieving the thinner portions of the blade from excessive 20 stresses.

Apparatus embodying the features of my invention is shown in the accompanying drawings, forming a part of this specification, and wherein:

25 Fig. 1 is an elevation of a portion of a turbine wheel, showing the blading mounted thereon; and,

Fig. 2 is an elevation of a turbine blade embodying a modified form of my invention.

30 According to my invention, the thinner portions of the blade are slightly distorted so as to produce a bulge, or a number of corrugations. The bulge, or the corrugations, are located where the greatest stress would 35 otherwise occur. By virtue of this construction, a blade is able to yield more freely than heretofore, and consequently, the stress in the thinner portions is reduced. This construction prevents rupture of the thin edge 40 portions and makes the blade capable of retaining its proper form for longer periods under all conditions of service.

In Fig. 1, I show a turbine wheel 10 in which are mounted a number of turbine 45 blades 11, the latter being provided with suitable lashing 12. In the blades shown, the point of maximum stress due to bending occurs at 13.

In order to relieve the thinner portions of

the blade from the excessive stresses which 50 occur, I provide a suitable number of transverse corrugations 14 substantially at the point 13. These corrugations 14 extend preferably only through the edge portions of the blade and while they are shown in only 55 one edge of these blades, it will be obvious that I may provide such corrugations in either, or both edges of the blades, should conditions render this advisable. These corrugations render the blade somewhat less 60 rigid in the thinner portions thereof so that the edges of the blade are more readily able to bend in response to vibrations which are set up in the operation of the turbine.

In place of the corrugations 14, I may 65 merely provide a bulge 16, as shown in Fig. 2. This bulged portion functions in the same manner as the corrugations, but would probably result in producing a greater change in the direction of fluid flow, and for 70 this reason I prefer the corrugations 14.

While both the bulge 16 and the corrugations 14 are shown as extending only through the thinner portions of the blade, it will be obvious that they may extend entirely across the blade should this be deemed 75 advisable. Furthermore, it is well known that turbine blades often vibrate at different frequencies under different conditions of operation so that nodes and antinodes are 80 produced at different points. It will be obvious that under such conditions there might be another point in addition to the point 13 at which a node would appear in operation and at which either a bulge, such 85 as shown at 16 in Fig. 2, or corrugations as shown at 14 in Fig. 1, might be required.

While I have shown my invention in two forms, it will be obvious to those skilled in the art that it is not so limited, but is susceptible of various other changes and modifications without departing from the spirit thereof, and I desire, therefore, that only such limitations shall be placed thereupon as are imposed by the prior art.

90 What I claim is:

1. A turbine blade having one or more corrugations extending in the direction of

fluid flow thereover, said corrugations extending only through the edge portions of the blade.

2. A turbine blade according to claim 1 wherein the one or more corrugations are located only substantially at the point where the greatest stress would otherwise occur.

3. A turbine blade according to claim 1

wherein the one or more corrugations are located only substantially at the point where 10 a node occurs during vibration of the blade.

In testimony whereof, I have hereunto subscribed my name this 8th day of December, 1927.

JAMES L. RAY.
